Primary Examiner — Antoine D Davis

(74) Attorney, Agent, or Firm — McAndrews Held & Malloy, Ltd.

(57) **CLAIM**

The ornamental design for a wearable sensor, as shown and described.

DESCRIPTION

FIG. 1 is a top perspective view of a wearable sensor showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

The dashed broken lines in the figures represent unclaimed portions of the wearable sensor and form no part of the claimed design.
